TIRE

Lemuel G. Burnett, Norristown, Pa., assignor to The
B. F. Goodrich Company, New York, N.Y., a corpora-
tion of New York

Filed Dec. 11, 1969, Ser. No. 20,453

Term of patent 14 years

Int. Cl. D12—14

U.S. Cl. D90—20

The figure is a perspective view of a tire showing my new design.

It is to be understood that the tread pattern continues as shown throughout the circumference of the tire and is the characteristic feature of the design.

I claim:

The ornamental design for a tire, substantially as shown and described.
